[57] **CLAIM**

The ornamental design for a handwheel and pivoting
handle therefor, as shown.

DESCRIPTION

FIG. 1 is a side elevational view of a handwheel and
pivoting handle therefor, showing my new design.

FIG. 2 is a top plan view of FIG. 1;

FIG. 3 is a bottom plan view of FIG. 1; and

FIG. 4 is an enlarged top perspective view of FIG. 1
with the handle in the extended position.

FIG. 1

FIG. 2

FIG. 3
